COUPLING FOR ELECTRIC CARS.

No. 426,317.

Patented Apr. 22, 1890.

UNITED STATES PATENT OFFICE.

LOUIS PFINGST, OF BOSTON, MASSACHUSETTS.

COUPLING FOR ELECTRIC CARS.

SPECIFICATION forming part of Letters Patent No. 426,317, dated April 22, 1890.

Application filed February 27, 1890. Serial No. 341,947. (No model.)

To all whom it may concern:

Be it known that I, LOUIS PFINGST, of Boston, in the county of Suffolk, State of Massachusetts, have invented certain new and useful Improvements in Couplings for Electric Cars, of which the following is a description sufficiently full, clear, and exact to enable any person skilled in the art or science to which said invention appertains to make and use the same, reference being had to the accompanying drawings, forming part of this specification, in which—

Figure 1 is a bottom plan view of two cars, showing my improvement in use; Fig. 2, a top plan view of the link; Fig. 3, a sectional elevation showing details of construction, and Fig. 4 a front elevation of the hanger.

Like letters and figures of reference indicate corresponding parts in the different figures of the drawings.

My invention relates especially to couplings for electric street-railway cars, the object being to overcome lost motion usual in couplings of this class and jar on the tow-cars incidental to stopping and starting the train.

The nature and operation of the improvement will be readily understood by all conversant with such matters from the following explanation.

In the drawings, A B represent the cars of a train provided with my improved coupler. The parallel braces b d are secured centrally and longitudinally on the bottoms of the cars. On the body of the car above the ends of these braces a metallic buffer D is secured, as shown in Figs. 3 and 4. Pendent from the ends of the braces and secured thereto by bolts and nuts f there is a metallic loop or hanger C, having a horizontal bottom g.

Secured to the bottom of the car-bodies between the trucks and braces b d there are metallic spring-boxes h. These boxes are open on their bottoms at i and at j in their rear ends. (See Fig. 3.)

The draw-bar H is fitted to slide longitudinally through said boxes and is provided with a horizontally-slotted head k, after the manner of the ordinary link-and-pin draw-bar. A rectangular plate m (see Fig. 3) is disposed loosely on the draw-bar, and is fitted to slide in the box h. Shoulders p on said bar engage

the plate and force it inward in the box on the rearward movement of said bar. A similar plate q is loosely disposed on the draw-bar at the opposite end of the box, said plate 55 engaging a vertical shoulder or flange r on the box bottom near the opening j. Secured on the draw-bar between the plate q and the inner end t of the box there is a block or ring v. A stiff coiled spring J is disposed around 60 the draw-bar within the box h, the ends of said spring being secured on studs w x on the plates m q, respectively.

A horizontally - arranged supplemental draw-bar K rests centrally on the bottom g 65 of the hanger C, and has one end secured in the head k of the draw-bar H by means of a pin 15, said pin being secured therein by a key or pin 16.

The link P consists of a box, rectangular in 70 cross-section, provided with a horizontal chamber 17, extending inward from each end and adapted to receive the free end of the bar K. Each end of the link is provided with a vertical pin-opening extending across said chamber 75 and adapted to receive coupling-pins 18. An eye 19 is formed on the link, and chains 20 connect each pin with said eye.

The supplemental draw-bars K have pin-openings in their outer or free ends adapted 80 to register with the corresponding openings in the link.

In the use of my improvement the link is secured by a pin 18 to the draw-bar K of the motor-car. The draw-bars of the train-cars 85 being sustained in the same horizontal plane by the hanger C when the motor-car is backed against said train-cars to shackle them, the train-car draw-bar may readily be directed into the open end of the link and secured by 90 a pin 18. The shock resultant from the coupling of the cars is cushioned by the spring J. The plate m, met by shoulders p p on the draw-bar H, is driven into the box h and said spring compressed.

The pins 15 and 18 having no play in the pin-holes of the draw-bars or link when the train is started the bar H is drawn outward through the box, its block v engaging the plate q, compressing the spring and relieving 100 the check on the tow-cars. By the use of my improvement the momentum of the tow-car,

which ordinarily tends to drive it forcibly against the motor-car in stopping, is sufficient to overcome jarring.

By means of the supplemental draw-bar 5 pivoted at its inner end to the main bar H by pin 15, sufficient lateral movement is allowed to permit the cars to readily pass around curves in the track.

The coupling proper as thus arranged on 10 each car has no longitudinal play independent from that on the adjacent car, and such joint movement is cushioned on the spring J.

Having thus explained my invention, what I claim is—

15 1. In a car-coupler, a spring-cushioned draw-bar, a supplemental draw-bar pivoted to swing laterally thereon, a link comprising a rectangular box chambered to receive an end of said supplemental bar, and a pin for 20 securing it thereto, substantially as described.

2. In a car-coupler, a spring-box secured to the car-body, a main draw-bar fitted to slide in said box, a spring for cushioning said bar, a supplemental draw-bar pivoted to said 25 main bar, and a link comprising a box chambered to receive an end of said supplemental bar adapted to be secured therein by a coupling-pin, substantially as described.

3. In a car-coupling, a link comprising a 30 bar chambered longitudinally at each end to receive a draw-bar and provided with openings for coupling-pins, substantially as described.

35 4. In a car-coupling, the link P, provided with chambers 17, for receiving a draw-bar,

and openings extending across said chambers for the coupling-pins, substantially as set forth.

5. In a car-coupling, the combination of a box secured to the car-body, a spring-cushioned main draw-bar sliding longitudinally therein, a supplemental draw-bar detachably pivoted to the head of said main bar, a hanger on the car provided with a horizontal bottom for supporting said supplemental 40 bar, and a link chambered to receive the outer end of said bar, and provided with openings for a coupling-pin whereby it may be secured therein, substantially as described.

6. In a car-coupler, the combination of a 50 spring-cushioned draw-bar sliding longitudinally on the car-body, with a supplemental draw-bar pivoted thereto, and supported by a hanger on the car, a link comprising a box or bar chambered to receive an end of said 55 supplemental bar, and coupling-pins for detachably securing said bar therein, the pin-openings being arranged to prevent longitudinal play of the link and bar, substantially as described. 60

7. In a car-coupling, the spring-cushioned bar H, provided with the head k, in combination with the bar K, secured thereto by the pin 15, the hanger C, the link P, chambered at 17, and the pins 18, arranged to operate 65 substantially as described.

LOUIS PFINGST.
